CLAIM

The ornamental design for a luggage, as shown and described.

DESCRIPTION

FIG. 1 is a front, right and top perspective view of a luggage, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of the luggage, shown in a used status; and,

FIG. 10 is an enlarged detail view of portion 10 encircled in FIG. 1.

The broken lines shown in the drawings illustrate portions of the luggage that form no part of the claimed design.

The dot-dash broken lines depict the boundaries of the enlargements that form no part of the claimed design.
